UNITED STATES PATENT OFFICE.

FRANCIS M. SMITH, OF SEATTLE, WASHINGTON.

COMBINATION TIE-PLATE, RAIL-ANCHOR, AND RAIL-BRACE.

1,070,926.

Specification of Letters Patent. Patented Aug. 19, 1913.

Application filed March 31, 1913. Serial No. 757,793.

To all whom it may concern:

Be it known that I, FRANCIS M. SMITH, a citizen of the United States, residing at Seattle, in the county of King and State of Washington, have invented new and useful Improvements in Combination Tie-Plates, Rail-Anchors, and Rail-Braces, of which the following is a full, clear, concise, and exact description, reference being had to the accompanying drawing, forming a part of this specification.

My invention relates to an improved combination tie plate, rail anchor and rail brace.

The objects of my invention are to provide, in a single device, a structure which satisfactorily performs the functions of the three devices above enumerated; to provide such a device in a form which lends itself to economical manufacture, and which may be readily applied to the rail; and to provide a device which, after being applied to the rail, maintains an effective hold thereon, throughout long continued service.

Other objects may be readily inferred, and numerous advantages inherent in the preferred form of device illustrated herein will be apparent from the subsequent description thereof.

The invention is, of course, not limited to the embodiment thereof illustrated, as it may be embodied in other forms.

In the drawings, Figure 1 is an end elevation, and Fig. 2 is a top plan view of a structure which will serve to illustrate the invention.

The rail 1 is illustrated as being supported by the usual cross tie 2, the combined tie plate, rail anchor and rail brace being secured to the rail and tie and interposed between the two. Said combined device consists of a base or plate 3, arranged between the base of the rail and the tie, and performing the usual function of a tie plate. Said plate may be provided with a plurality of downwardly extending ribs 4, adapted to be pressed into the wood fibers to increase the anchorage of the tie plate on the tie. It is provided further with a pair of jaws 5, 6, which are preferably integral therewith and arranged at or near opposite corners thereof. Said jaws are adapted to fit over the rail base when the device is in operative position, as shown particularly in Fig. 1. The adjacent corners of said jaws are cut away or beveled, as shown at the points 7, 8, the distance between these beveled portions being somewhat greater than the width of the rail base. The openings of the jaws are originally somewhat larger than the corresponding sides of the rail base which they are intended to fit, being about as shown in dotted lines in Fig. 1. Accordingly, the device may be very readily applied to the rail by lifting the latter and adjusting the tie plate to the base thereof, said tie plate being applied first in a diagonal position so as to permit the rail base to be cleared by the beveled corners of the jaws 5, 6, and the tie plate being thereafter moved around to the position shown in Fig. 2. Said tie plate is provided on one side with a rib or shoulder 9 against which one side of the rail base abuts. It is mainly because of this shoulder that the loosely fitting jaws are provided; otherwise, the device could not be skewed around to the desired position of final adjustment. After making said final adjustment, the jaws, which may be assumed to be malleable iron, are hammered down onto the top of the rail base, as shown in full lines in Fig. 1. In this position, the jaw 6 fits snugly over the portion of the rail base which it embraces. The jaw 5 is under-cut, however, so as to provide a clearance between the edge of the rail base and the adjacent vertical wall thereof. Said vertical wall is arranged somewhat diagonally, whereby a suitable wedge or key 10 may be driven therein to crowd the rail against the shoulder 9 and to firmly bind the same between said shoulder and said wedge, thereby preventing creeping. In order to prevent a rearward movement of the wedge and a consequent loosening of the hold on the rail base, a spike 11, which may be a standard spike, is driven through a suitably arranged opening in the tie plate and abuts against the end of the wedge, thereby positively locking the latter in position. Additional spikes 12, 13 are driven through openings in the opposite side of the tie plate, thereby firmly holding the latter to the tie and preventing twisting thereof. With the arrangement of parts shown, the tie is prevented from skewing, and thus helps maintain the proper gage and alignment of the rails. The shoulder 9 is arranged preferably against the outer edge of the rail, whereby said shoulder and jaw 6 prevent the rail from spreading. For this purpose, the device may be designed in right- and left-hand structures. The jaws also prevent overturn-

- ing of the rail. Said jaws, as seen, are adapted to overlie the upper surface of the rail to a considerable extent, thereby increasing their effectiveness in this respect.
- 5 Any tendency of the rail to creep in the direction shown by the arrow in Fig. 2 will cause an increase in the wedging engagement. Creeping is also prevented in the opposite direction, because of the firm frictional hold of the parts, which is insured by the positive locking of the wedge 10 in position. Said wedge cannot become loosened, either by vibration or contraction of the rail.
- 10 15. The rail anchor and tie plate, after being applied to the rail, will not fall off when the rail is subsequently elevated in replacing the ties. This is an advantageous feature, as it saves careful readjusting of the tie plates on the new ties. The rail anchor is constructed preferably of malleable iron, whereby it is not readily broken or injured by derailments.
- 15 I am aware that various changes may be made in the details of the construction described herein, without departing from the spirit of the invention. Accordingly, I do not limit myself to the embodiment disclosed, but desire to cover whatever modifications thereof fall within the scope of the appended claims.
- Having thus described my invention, what I claim as new and desire to secure by Letters Patent of the United States is:
- 30 35. 1. In combination, a tie plate, a pair of opposed rail gripping jaws thereon, one of
- said jaws being arranged in advance of the other, a shoulder on one side of said tie plate adapted to bear against the edge of the rail base, a wedge fitting within the jaw on the side opposite said shoulder, said wedge serving to crowd the rail base against said shoulder and to firmly grip the same, and means for positively locking said wedge against a movement which would cause it to loosen its grip.
2. In a device of the class described, a plate having sharp ribs on the under side thereof adapted to be pressed into a tie, a rail gripping jaw on each side of said plate, said jaws being arranged at opposite corners of said plate and having their adjacent corners cut away to provide a clearance between them somewhat in excess of the width of the rail base, a shoulder on one side of said tie plate extending from the adjacent jaw to the end of said plate, said shoulder having a pair of spike openings therein, an additional spike opening on the opposite side of said plate adjacent to the other jaw, and a wedge adapted to be received within said other jaw and to bear against the adjacent side of the rail base, the large end of said wedge terminating at said last mentioned spike opening.
- 65 In witness whereof, I have hereunto subscribed my name in the presence of two witnesses.
- FRANCIS M. SMITH.
